ADOLF CLAËS SEBASTIAN VON WACHENFELDT, OF LUND, SWEDEN, ASSIGNOR TO KIRURGiska INSTRUMENT FABRIKS AKTIEBOLAGET, OF STOCKHOLM, SWEDEN, A JOINT-STOCK COMPANY

WOUND CLASP

Application filed June 21, 1928, Serial No. 287,282, and in Sweden July 2, 1927.

Nowadays it is common practice in surgical operations to use wound clasps or so-called agraffes to keep the edges of the wounds together during the healing of the wound, 5 said clasps being employed either as a substitute for the thread stitches previously used, or, in certain cases, in connection therewith.

Such wound clasps or agraffes generally consist of a thin metal strip formed at each 10 end into a loop and provided with pins projecting from the said loops, which pins are caused to penetrate into the skin on both sides of the cut when the clasp is bent about the edge of the wound, the clasp being thus 15 retained over the edge of the wound.

As a rule, this operation does not offer any difficulties to an operator accustomed to using the said clasps. On the other hand, difficulties are met with when, after the healing 20 of the wound, or before, if required, the clasp is to be removed from the edge of the wound. The difficulty substantially lies in removing 25 the pins from the wound in such a manner as to relieve the patient as far as possible of annoyance or pain, and so as not to irritate or damage the edge of the wound.

The present invention has for its object to obviate the said difficulty and, at the same 30 time, to facilitate removal of the clasp from the edge of the wound by means of ordinary simple instruments, such as common forceps, pincers or the like, or even by means of the fingers of the operator.

The invention consists substantially in that 35 the clasp is provided with projections on the outside, which projections are swung in a direction from each other when the clasp is bent together over the edge of the wound, whereas as approaching of the said projections to- 40 ward each other will straighten out the clasp so that the pins of the same will be removed from the edge of the wound. The said pro- 45 jections may be situated either close to one another or at some distance from each other, in which latter case the angle of return of the ends of the clasp may be made larger. Preferably, the projections may be made integral with the clasp proper by bending of the metal strip forming the clasp.

50 A couple of embodiments of a clasp ac-

cording to the invention are shown in the accompanying drawing in Figs. 1, 2 and 3, 4 and 5 respectively.

This clasp consists, as usually, of a metal strip 1 provided with loops 2 at the ends, from 55 which strip the pins 3 are cut out.

According to the invention the said strip 1 is provided on its outside with two pro- 60 jections 4 formed by double-bending of the strip and situated close onto each other ac- 65 cording to Fig. 1, whereas in the embodiment according to Fig. 3 they are located at a certain distance from each other, so that their outer ends will be brought further apart than in the embodiment according to Fig. 1 when 70 the clasp is bent together over the edge of the wound, as will be seen by a comparison be- 75 tween Figs. 2 and 4. On account of this it will also be possible at the following return- 80 bending or straightening of the clasp to move 70 the pins further apart, which may be of ad- 85 vantage in certain cases.

When the clasp is bent back by pressing the 85 projections 4 together, which may be effected by means of common forceps, pincers or the like, as previously stated, the pins 3 will be moved, simultaneously and uniformly, out 90 of contact with the edge of the wound to such an extent that the clasp may be removed without difficulty. Also, no special skillfulness nor care is required in this operation.

It is obvious, that the clasp may also be 95 made out of a suitably bent wire loop or the like, without departing from the principle of the invention, or, as illustrated in Fig. 5, 85 by double-bending a metal strip with the pro- 90 jections bent outwardly from the upper parts of the metal strip.

What I claim as new and desire to secure 95 by Letters Patent of the United States of 90 America is:—

1. A wound clasp or so-called agraffe consisting of a metal strip or of a suitably bent wire loop or the like which is provided at the ends with pins adapted to be introduced into the skin when the clasp is closed over the edge of the wound, characterized by the clasp being provided on the outside with projections arranged in such a manner that the latter will be swung in a direction from each other when 100

the clasp is closed over the edge of the wound, whereas approaching of the said projections towards each other will straighten out the clasp so that the pins of the same will be removed from the edge of the wound.

2. A wound clasp according to claim 1, characterized by the projections arranged on the outside of the clasp being located close beside each other.

10 3. A wound clasp according to claim 1, characterized by the projections arranged on the outside of the clasp being made integral with the clasp proper.

In testimony whereof I affix my signature.
